UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

Application filed September 24, 1923. Serial No. 664,368.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 This invention relates to typographical machines, such as linotype machines of the general organization represented in U. S. Letters Patent No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters, and the matrices thereafter elevated and returned through distributing mechanism to the magazine from which they started.

25 More particularly, it relates to machines of the class disclosed in my prior Letters Patent No. 1,396,125, and contemplates certain improvements intended to simplify the construction of the parts and to render them more efficient in operation. These improvements will best be understood from the detailed description to follow.

Referring to the drawings:

Fig. 1 is a side elevation of a portion of a linotype machine equipped with the present improvements;

Fig. 2 is a top plan view of the magazine structure;

Fig. 3 is a section taken on the line 3—3 of Fig. 2;

Fig. 4 is a section taken on the line 4—4 of Fig. 3;

Fig. 5 is a perspective view of one of the gage blocks detached;

Fig. 6 is a view similar to Fig. 1 but showing the parts in different position;

Fig. 7 is a detail section taken on the line 7—7 of Fig. 6;

Fig. 8 is a detail section taken on the line 8—8 of Fig. 6;

Figs. 9 and 10 are detail views of the improved brake device employed in connec-

tion with the magazine shifting means, Fig. 9 being a section taken on the line 9—9 of Fig. 10, and Fig. 10 being a section taken on the line 10—10 of Fig. 9; and

Fig. 11 is a detached perspective view of the spring-pressed plunger forming a part of the brake device.

The matrices X are stored according to 60 font in superposed channeled magazines A, four of which are shown herein but of which a greater or less number might be employed if desired. The several magazines are mounted upon separate base-frames A¹ 65 conjointly constituting a "shift-frame," which is arranged to be moved upwardly and downwardly in the fixed machine frame to bring any selected one of the magazines into operative relation to a channeled assembler 70 entrance B and a channeled magazine entrance C, the latter leading from a distributor D. Each of the magazines A is provided with matrix releasing escarpments E (Fig. 6), which, when the magazine is brought 75 into operative position, are actuated through the medium of pivoted levers E¹ by reeds E² controlled in the usual way from a keyboard E⁴ (Fig. 1). The magazine shift-frame is carried by a sliding plunger L³ which is 80 raised and lowered within a sleeve O by a screw-thread mechanism L⁵ actuated through a connecting shaft L² by a wheel L provided with an operating handle L¹, all as more 85 fully described in the Rogers Patent No. 1,109,872.

Means are provided to cooperate with each magazine independently as it is brought into operative position and locate it with certainty in proper relation to the cooperating 90 parts. Specifically, three distinct sets of gage-devices are arranged to engage aligning lugs on the base-frame of the selected magazine as the latter is shifted into operative position and adjust said frame independently relatively to the others in three different directions, namely, facewise or vertically to locate the magazine thereon in proper transverse registration with the assembler-entrance and magazine-entrance, 95 respectively; edgewise or toward the left and right to locate the magazine in proper lateral registration with the two entrances; and, finally, endwise or fore and aft to lo-

cate the magazine in proper longitudinal position for cooperation with said entrances. As illustrated, each of the three upper base-frames A¹ is formed at its rear end and at 5 opposite sides with pivot pins A² which engage in open notches or recesses A³ formed in the rear edges of a pair of plates A⁴ attached to and rising from the lowermost base-frame, it being noted that these notches 10 A³ are large enough to permit the pivot pins A² to have the necessary amount of play. At their forward ends, each of the three 15 upper base-frames is provided at opposite sides with depending blocks A⁵ resting directly upon the next underlying magazine and which, while maintaining the base frames properly spaced apart, permit them to be shifted relatively to each other in the required manner. The lowermost base- 20 frame A¹ is also mounted so as to be independently adjustable in the same manner as each of the three upper base-frames, being fastened to a collar portion L⁴ of the plunger L³ by means of shouldered studs A⁶ passing 25 loosely through enlarged openings A⁷ formed therein (Fig. 6).

The transverse registration of the magazine in use is effected by means of two pairs of gage-bars F arranged near the opposite 30 ends of the magazines and at opposite sides thereof, the two bars at each side being connected together by a fore and aft piece F¹. These gage-bars F are supported at their lower ends upon aligning blocks F³ attached 35 to fixed side plates O² and O³ of the machine frame and present their upper ends in position to engage the under sides of aligning lugs F² projecting laterally from the opposite sides of each base-frame at both 40 ends. The foregoing parts are so arranged and operated that when any selected magazine is brought into operative position, the aligning lugs F² of its base-frame A¹ will be caused to bank upon the gage-bars F, 45 which thus adjust said base-frame facewise bodily relatively to the other base-frames and locate the magazine thereon in proper transverse registration with the assembler entrance B and magazine entrance C, respectively. To provide for the engagement of 50 the gage pieces F with the aligning lugs F², the former are arranged to slide forwardly and rearwardly on the aligning blocks F³, so as in one position to stand clear of the aligning lugs during the shifting of the magazines, and in the other position to stand beneath the lugs on the base-frame of the selected magazine to allow said frame to bank thereon. When one of the 55 upper magazines is brought into use, the aligning lugs F² on the base-frames of the underlying magazines would engage the gage-bars and prevent their return to active position, unless otherwise provided for. 60 Hence, the gage-bars F are formed in their

rear edges with notches f which allow them to clear the aligning lugs at such time, these notches being made considerably wider than the aligning lugs so as not to interfere with the lowering of the magazines, which takes 70 place in banking the operative magazines on the gage-bars. This lowering of the magazines, however, is limited by the engagement of the aligning lugs on the lowermost base-frame with the bottom walls of the 75 particular notches wherein they are located (Fig. 6).

The lateral registration of the operative magazine is effected by means of a pair of gage-blocks or abutments G supported in 80 the aforesaid side plates O³ at opposite sides of the magazines in position to engage the outer faces of the aligning lugs F² at the forward ends of the base-frames A¹. These blocks G are adjustable transversely of the 85 magazines and are set and held in the required position by adjusting screws G² and clamping screws G³ (Fig. 4), the former bearing against the outer edges of the blocks, and the latter passing through elongated 90 slots formed therein. At their inner edges (Fig. 5), the blocks G are formed with aligning surfaces G⁴ and with oppositely beveled surfaces G⁵ leading thereto. Accordingly, when a selected magazine is 95 brought into operative position, the aligning lugs F² at the lower end of its base-frame A¹ are automatically engaged with the gage-blocks G, whose beveled surfaces G⁵ adjust said frame edgewise toward the 100 left or right, as the case may be, until the aligning surfaces G⁴ become engaged with the outer faces of the aligning lugs, which engagement of the parts determines the lateral registration of the magazine with the 105 assembler entrance B.

The location of the operative magazine in proper longitudinal position is effected by a pair of gage-blocks or abutments H also supported in the side plates O³ at opposite sides of the magazines in position to engage the forward faces of the aligning lugs F² as the individual magazines are brought into use. These gage-blocks H (Fig. 110 3) are slidably arranged in fore and aft grooves or guideways H¹ wherein the blocks are confined by clamping screws H² passing through elongated slots formed in the side plates O³. The proper position of the gage-blocks is controlled and regulated by adjusting screws H² bearing against the forward edges thereof. At their rear edges, the blocks H are formed with aligning surfaces H⁴ and beveled surfaces H⁵, so that as a selected magazine is shifted into position, the lower aligning lugs F² on its base-frame are engaged with the beveled surfaces H⁵, which adjust the frame endwise if need be 115 until the forward faces of its aligning lugs become engaged with the aligning surfaces 120 125 130

H⁴ of the gage-blocks. In this way, the selected magazine is located independently in proper longitudinal position within the shift-frame for cooperation with the assembler and magazine entrances.

The foregoing parts and their mode of operation, except as hereinafter pointed out, are or may be the same as set forth in my prior Patent No. 1,396,125. As before stated, the present invention is directed to certain improvements in the machine disclosed in said patent, and these improvements will now be taken up in detail.

One improvement is directed to an arrangement whereby the gage-bars F may be adjusted independently or relatively to one another to insure their mutual cooperation in effecting the transverse registration of the individual magazines. In the present instance, the aligning blocks F³, instead of being made integral with the fixed side plates O² and O³ (as in my prior patent), are made separate from said plates and are adjustably mounted thereon so as to raise or lower the gage-bars in the direction of their longitudinal axes. The purpose of this adjustment is not only to compensate for inaccuracies in the manufacture of the parts, but in addition to insure the proper cooperation between the gage-bars and the aligning lugs F² on the base-frame of the magazine in use. One of the chief difficulties encountered in practice is that the magazine base-frames frequently lose their original shape, due to warping or other causes, and interfere with the proper banking of the aligning lugs upon the gage-bars. This difficulty may be easily overcome in the present construction by adjusting one or another of the aligning blocks in such manner as to locate the gage-bars in whatever position may be necessary to cooperate with the aligning lugs. As a simple and convenient way to adjust the aligning blocks F³, they are formed on their under sides with inclined or wedge-shaped surfaces f³ slidingly arranged upon reversely inclined or wedge-shaped surfaces of supporting blocks O⁴ located at the inner sides of the side plates O² and O³, clamping screws O⁵ being employed to hold the aligning blocks in any desired position of adjustment, see particularly Figs. 6 and 8.

Another improvement has to do with the movement of the gage-bars F to and from active position. In my aforesaid prior Letters Patent, such movement of the gage-bars is controlled by the magazine shifting means, but in the present construction, it is effected by separate and independent means comprising, as herein shown (Fig. 1), a hand lever F⁶ located adjacent the magazine shifting handle L¹, a transverse rock shaft F⁵ to which the hand lever is made fast, and a pair of upright arms F⁴ also made fast to the rock shaft and arranged behind and

in engagement with pins F⁷ projecting inwardly from the connecting links F¹. Springs F¹¹ pulling rearwardly on the connecting links serve to hold the parts in their normal condition. As a result of this construction, when the hand lever F⁶ is depressed, the arms F⁴ are rocked forwardly and move the gage-bars F to inactive position against the opposition of the springs F¹¹, which immediately restore the parts to their original condition upon the release of the hand lever. It will be seen, therefore, that by operating the hand lever F⁶ with one hand and the hand wheel L with the other, the operator may quickly and easily carry out the shifting of the magazines to bring any selected one into operative position. At the beginning of the shifting operation, the magazines are raised slightly so as to relieve the pressure upon the gage-bars F and permit them to be moved freely to inactive position, and similarly at the close of the shifting operation, the selected magazine is brought to a level slightly above that it will eventually occupy, so as to permit the gage-bars to be moved freely to active position before the selected magazine is caused to bank thereon by the lowering of the magazines. The use of a separate and independent hand lever for operating the gage-bars is particularly suitable for this method of magazine shifting, as it enables the operator to synchronize and carry out the operations with greater ease and rapidity than would otherwise be possible.

As a further improvement, it is pointed out that the hand lever F⁶ has connected to it by means of a link P¹, a matrix blade or feeler P which is arranged to be slid upwardly and downwardly in the space between the operative magazine and the assembler entrance B (Fig. 1). Normally, or when the gage-bars F occupy their active position, the blade P stands above and out of the path of the matrices issuing from the magazine, but when the gage-bars are drawn forwardly to their inactive position by the depression of the hand lever F⁶, the blade is pulled downwardly by the lever across the matrix path. Consequently, if at the time there should be any matrix or matrices protruding from the lower end of the magazine, the blade will be arrested by such protruding matrix or matrices and will lock the gage-bars against movement to inactive position. In this way, the shifting of the magazine is prevented except when the matrices are properly enclosed within it.

Another improvement deals with the means employed for locating the individual magazines in proper longitudinal position within the shift frame. By reason of the freedom of movement allowed the magazines in providing for such longitudinal

positioning, it sometimes happens that the selected magazine, while being shifted into and out of operative position, will project forwardly to such extent as to interfere, 5 or cause its escapements to interfere, with the upper end of the assembler entrance B or the escapement actuating levers E¹. In order to obviate this difficulty, the gage-blocks H have been modified in such manner 10 that they will locate and maintain the selected magazine in its proper longitudinal position within the shift frame long enough before it reaches and after it leaves its actual operative position during shifting to 15 avoid interference with the other parts. Thus, as can be seen from Figs. 3 and 6, the aligning surfaces H⁴ are of much greater extent than those presented in my prior construction, being lengthened out sufficiently 20 to produce the effect just noted, and the beveled surfaces H⁵ are located at correspondingly greater distances from the aligning blocks F² so as to act thereon at earlier and later periods in the shifting of the 25 magazine.

As a further improvement in connection with the longitudinal positioning of the magazines, it may be noted that the aligning lugs F² are provided with adjustable 30 contact pieces, herein shown in the form of flat-headed screw bolts f² (see particularly Figs. 3 and 4). These contact pieces have been found to be very advantageous 35 in providing for the proper cooperation between the aligning lugs F² and the gage-blocks H, being readily adjustable to compensate for any irregularities in alignment due to wear, faulty manufacture, or warping of the base frames, etc. The aligning 40 lugs on the lowermost base frame are not provided with such adjustable contact pieces, although they might be, as the gage-blocks themselves may be adjusted to take care of that particular magazine by manipulating the screws H² and H³ in the manner before described.

Another improvement is directed to the magazine shifting means, which, as before described, include the screw L⁵ rotatable 50 in opposite directions by the operating shaft L². In practice, it has been found that the screw L⁵ has a tendency to "spin" during the lowering of the magazines, due to the heavy pressure imposed upon the screw threads by the great weight of the magazine structure. When this occurs, the operator has considerable difficulty in maintaining the parts under control, and, unless great care is observed, he is apt to lose 55 control altogether. As a simple and convenient way to overcome this difficulty, it is proposed to employ a brake device which will serve to retard the lowering of the magazines but which will permit the raising thereof without retardation. In the

present instance (see Figs. 9 to 11), the brake device comprises a split sleeve R frictionally clamped to the operating shaft L² by means of a screw R¹ and spring R², the screw passing loosely through an opening 70 formed in the upper part of the split sleeve and threaded into an opening tapped into the lower part of the sleeve, and the spring being interposed between the head of the screw and the upper part of the split sleeve, 75 all as clearly shown in Fig. 9. As will be apparent, by adjusting the screw R¹, the spring R² may be tensioned to cause the split sleeve to exert upon the shaft L² whatever friction may be required. As preferred, 80 the sleeve R is provided with liners R³ made of leather or any other suitable material. Mounted within a suitable recess of the sleeve R is a spring-pressed plunger R⁴ protruding from the rear face thereof and 85 formed with an inclined or beveled surface R⁵; and a stop or abutment R⁶ is located on the fixed bearing member O⁶ in position to engage said spring-pressed plunger R⁴. According to this arrangement, when the 90

shaft L² is rotated in a clockwise direction to raise the magazines, the stop R⁶ will engage the beveled surface R⁵ of the spring-pressed plunger R⁴ and push the latter inwardly out of the way, thereby permitting the friction sleeve R to be rotated with the shaft so as to offer no resistance thereto. On the other hand, when the shaft L² is rotated in a counter-clockwise direction to lower the magazines, the stop R⁶ will engage the solid portion of the spring-pressed plunger R⁴ and thereby lock the sleeve R against rotation with the shaft, so that the rotation of the shaft under such conditions will have to be effected against the frictional resistance offered by the sleeve. It will be understood that this frictional resistance may be regulated so as merely to counteract the spinning tendency of screw F⁵ and not so great as to require any substantial effort on the part of the operator. To avoid any tendency of the sleeve R to shift forwardly on the operating shaft L², the latter, if desired, may be provided with a collar R⁷ held thereto by a set screw R⁸ 105 and arranged in engagement with the forward face of the sleeve.

As in my prior patent, mechanism is employed for separating the base frames from each other in order to permit the independent removal of the magazine, such mechanism comprising the hand lever J, the transverse rock shaft J¹, the arms J², the links J³, and the lost motion devices or lifting links J⁵. However, as these parts are precisely the same as described in said patent, no further explanation seems necessary.

It may also be noted that means are provided for effecting the lateral registration of the magazine entrance C with the par-

ticular magazine in use, such means (Figs. 6 and 7) comprising gage pieces S secured to each magazine base frame at its upper end and on opposite sides and which are 5 adapted to engage in grooves or recesses S¹ of aligning lugs S² secured to the entrance frame C just above and in the rear of its pivotal point. Such means, however, 10 form no part of the present invention and are fully disclosed in my prior Letters Patent No. 1,396,126, to which reference may be had.

As previously stated, the present improvements have been shown only in preferred form and by way of example and as applied to a particular class of machine, but obviously many modifications and alterations therein and in their mode of application will suggest themselves to those 20 skilled in the art without departure from the scope of the invention.

Having thus described my invention, its construction and mode of operation, what I claim and desire to secure by Letters Patent of the United States is, as follows:

1. In a typographical machine, the combination of a channeled member, a shift-frame equipped with a plurality of channeled magazines supported therein with a 30 capacity for relative play in a facewise direction, means for moving the shift-frame to bring one or another of the magazines into operative relation to said channeled member, gage-devices upon which the selected magazine is caused to bank independently as it is brought into operative position and which adjust it facewise within the shift-frame to locate it in proper transverse registration with the cooperating channeled 35 member, and means for adjusting the gage-devices relatively to one another to insure their mutual cooperation in effecting such registration of the parts.

2. In a typographical machine, the combination of a channeled member, a plurality of channeled magazines, separate base-frames whereon the magazines are mounted and each provided at one end and at opposite sides with a pair of laterally projecting alining lugs, means for connecting the base-frames together with a capacity for relative play in a facewise direction, means for shifting the base-frames as a whole to bring one or another of the magazines into 50 operative relation to said channeled member, a pair of transverse gage-bars supported in a fixed machine frame at opposite sides of the magazines in position to engage the alining lugs on the base-frame of the selected magazine as the latter is brought into operative position and thus to adjust said magazine facewise and locate it in proper transverse registration with the co-operating channeled member, and means for 55 adjusting the gage-devices relatively to one

another to insure their mutual cooperation in effecting such registration of the parts.

3. In a typographical machine, the combination of a channeled assembler-entrance, 70 a channeled magazine-entrance leading from the distributor, a plurality of intermediate channeled magazines, separate base-frames whereon the magazines are mounted and each formed at each end and at opposite

sides with a pair of laterally projecting 75 alining lugs, means for connecting the base-frames together with a capacity for relative play in a facewise direction, means for

shifting the base-frames as a whole to bring one or another of the magazines into operative 80 relation to the two entrances, two pairs of transverse gage-bars arranged at the four corners of the magazines with their upper ends in position to engage the alining

lugs on the base-frame of the selected 85 magazine, and independently adjustable alining blocks mounted in the fixed machine frame and upon which the gage-bars rest at their lower ends, whereby said gage-bars

may be adjusted independently to insure 90 their mutual cooperation in effecting the proper transverse registration of the selected magazine with the assembler-entrance and magazine-entrance, respectively.

4. In a typographical machine, the combination of a shift-frame equipped with a 95 plurality of magazines supported therein with a capacity for relative play in an endwise direction, means for moving the shift-frame to bring one or another of the magazines into operative position, and means for

adjusting the selected magazine endwise independently as it is brought into operative position to locate it in proper longitudinal 100 position within the shift frame for

cooperation with the other elements of the machine, said adjusting means acting to effect and to maintain such location of the selected magazine before it reaches and after

it leaves its operative position during shift- 105 ing, respectively.

5. In a typographical machine, the combination of a plurality of magazines, separate base-frames whereon the magazines are mounted, means for connecting the base-frames together with a capacity for relative 115 play in an endwise direction, means for shifting the base-frames as a whole to bring one or another of the magazines into operative position, and a pair of gage-blocks or

abutments supported in the fixed machine frame at opposite sides of the magazines in position to engage the base-frame of the selected magazine as the latter is brought into operative position and adjust said frame

endwise relatively to the others to locate the magazine thereon in proper longitudinal 120 position for cooperation with the other elements of the machine, said gage blocks acting to effect and to maintain such location

125

130

of the selected magazine before it reaches and after it leaves its operative position during shifting, respectively.

6. In a typographical machine, the combination of a plurality of channeled magazines, separate base-frames whereon the magazines are mounted and each provided at one end and at opposite sides with a pair of laterally projecting alining lugs, means for connecting the base-frames together with a capacity for relative play in an endwise direction, means for shifting the base-frames as a whole to bring one or another of the magazines into operative position, and a pair of gage-blocks supported at opposite sides of the magazines in position to engage the aligning lugs on the base-frame of the selected magazine as it is brought into operative position and locate said magazine in proper longitudinal position within the shift frame, the said gage-blocks being beveled at their opposite ends and formed with extended alining surfaces to effect and to maintain such location of the magazine before it reaches and after it leaves its operative position during shifting, respectively.

7. In a typographical machine, the combination of a plurality of channeled magazines, separate base-frames whereon the magazines are mounted and each provided at one end and at opposite sides with a pair of laterally projecting alining lugs, means for connecting the base-frames together with a capacity for relative play in an endwise direction, means for shifting the base-frames as a whole to bring one or another of the magazines into operative position, and a pair of gage-blocks supported at opposite sides of the magazines in position to engage the alining lugs on the base-frame of the selected magazine as it is brought into operative position and locate said magazine in proper longitudinal position within the shift frame, the alining lugs of one or more of the base-frames being provided with adjustable contact pieces to insure their proper cooperation with the gage blocks.

8. In a typographical machine, the combination of a plurality of magazines, separate base-frames whereon the magazines are mounted, means for connecting the base-frames together with a capacity for relative play in an endwise direction, means for shifting the base-frames as a whole to bring one or another of the magazines into operative position, a pair of gage-blocks or abutments supported in the fixed machine frame at opposite sides of the magazines in position to engage the base-frame of the selected magazine as the latter is brought into operative position and adjust said frame endwise relatively to the others to locate the magazine thereon in proper longitudinal po-

sition for cooperation with the other elements of the machine, and independent adjusting means for said gage-blocks to insure their mutual cooperation in effecting such longitudinal location of the selected magazine.

9. In a typographical machine, the combination of a channeled member, a plurality of channeled magazines, separate base-frames whereon the magazines are mounted, means for shifting the base-frames as a whole to bring one or another of the magazines into operative relation to said channeled member, a pair of gage-blocks or abutments supported in the fixed machine frame at opposite sides of the magazines in position to engage the base-frame of the selected magazine as the latter is brought into operative position and adjust said frame edgewise relatively to the others to locate the magazine thereon in proper lateral registration with the cooperating channeled member, and independent adjusting means for said gage-blocks to insure their mutual cooperation in effecting such lateral registration of the parts.

10. In a typographical machine, the combination of a channeled member, a plurality of channeled magazines, separate base-frames whereon the magazines are mounted and each provided at one end and at opposite sides with a pair of laterally projecting alining lugs, means for connecting the base-frames together with a capacity for relative play in a facewise direction, means for shifting the base-frames as a whole to bring one or another of the magazines into operative relation to said channeled member, a pair of transverse gage-bars supported in the fixed machine frame at opposite sides of the magazines in position to engage the aligning lugs on the base-frame of the selected magazine as the latter is brought into operative position and thus to adjust said magazine facewise and locate it in proper transverse registration with the cooperating channeled member, and means independent of the magazine shifting means for moving the gage-bars to and from active position.

11. In a typographical machine, the combination of a channeled member, a plurality of channeled magazines, separate base-frames whereon the magazines are mounted and each provided at one end and at opposite sides with a pair of laterally projecting aligning lugs, means for connecting the base-frames together with a capacity for relative play in a facewise direction, means for shifting the base-frames as a whole to bring one or another of the magazines into operative relation to said channeled member, a pair of transverse gage-bars supported in the fixed machine frame at opposite sides of the magazines in position to engage the

- 60
- aligning lugs on the base-frame of the selected magazine as the latter is brought into operative position and thus to adjust said magazine facewise and locate it in proper transverse registration with the co-operating channeled member, means independent of the magazine shifting means for moving the gage-bars to and from active position, and a matrix feeler connected to and operated by the gage-bar moving means.
- 65
12. In a typographical machine, the combination of a channeled member, a plurality of channeled magazines, separate base-frames whereon the magazines are mounted and each provided at one end and at opposite sides with a pair of laterally projecting aligning lugs, means for connecting the base-frames together with a capacity for relative play in a facewise direction, means for shifting the base-frames as a whole to bring one or another of the magazines into operative relation to said channeled member, a pair of transverse gage-bars supported in the fixed machine frame at opposite sides of the magazine in position to engage the aligning lugs on the base-frame of the selected magazine as the latter is brought into operative position and thus to adjust said magazine facewise and locate it in proper transverse registration with the co-operating channeled member, and a hand lever located adjacent to but independent of the magazine shifting means for moving the gage-bars to and from active position.
- 70
13. In a typographical machine, the combination of a channeled member, a plurality of channeled magazines, separate base-frames whereon the magazines are mounted and each provided at one end and at opposite sides with a pair of laterally projecting aligning lugs, means for connecting the base-frames together with a capacity for relative play in a facewise direction, means for shifting the base-frames as a whole to bring one or another of the magazines into operative relation to said channeled member, a pair of transverse gage-bars supported in the fixed machine frame at opposite sides of the magazines in position to engage the aligning lugs on the base-frame of the selected magazine as the latter is brought into operative position and thus to adjust said magazine facewise and locate it in proper transverse registration with the co-operating channeled member, and a hand lever located adjacent to but independent of the magazine shifting means for moving the gage-bars to and from active position, and
- 75
14. In a typographical machine, the combination of a channeled member, a plurality of channeled magazines, separate base-frames whereon the magazines are mounted and each provided at one end and at opposite sides with a pair of laterally projecting aligning lugs, means for connecting the base-frames together with a capacity for relative play in a facewise direction, means for shifting the base-frames as a whole to bring one or another of the magazines into operative relation to said channeled member, a pair of transverse gage-bars supported in the fixed machine frame at opposite sides of the magazines in position to engage the aligning lugs on the base-frame of the selected magazine as the latter is brought into operative position and thus to adjust said magazine facewise and locate it in proper transverse registration with the co-operating channeled member, and a matrix feeler connected to the gage-bars and serving to prevent their movement from active position at an improper time.
- 80
15. In a typographical machine, the combination of a plurality of magazines, means for raising and lowering said magazines to bring one or another into operative position, and a brake device acting to retard the lowering of the magazines but to permit the raising thereof without retardation.
- 85
16. In a typographical machine, the combination of a plurality of magazines, means including a rotary operating shaft for raising and lowering said magazines to bring one or another into operative position, a sleeve frictionally clamped to said operating shaft and rotatable therewith, and a stop arranged to lock said sleeve against rotation with the shaft during the lowering of the magazines but to permit its free rotation with the shaft during the raising of the magazines.
- 90
17. In a typographical machine, the combination of a plurality of magazines, means including a rotary operating shaft for raising and lowering said magazines to bring one or another into operative position, a sleeve frictionally clamped to said operating shaft and rotatable therewith, a spring-pressed plunger carried by said sleeve and beveled at its free end, and a stop mounted on a fixed part of the machine in position to engage said plunger.
- 95
18. In testimony whereof, I have affixed my signature hereto.

DAVID S. KENNEDY.
